CAR COUPLER

William J. Metzger, East Cleveland, Ohio, assignor to National Malleable and Steel Castings Company, Cleveland, Ohio, a corporation of Ohio

Application March 31, 1958, Serial No. 725,032

3 Claims. (Cl. 213—151)

This invention relates generally to railway knuckle-type car couplers, and more particularly to the contour of knuckle-receiving pockets thereof.

An important activity of the car building industry in the United States has been to provide standard couplers made of cast components requiring little machine finishing. That is to say, the components are separately cast with sufficient dimensional accuracy to permit assembly thereof as cleaned, trimmed castings requiring no machining, into couplers which are reliable for positive operation throughout a lengthy service period.

Typical of the knuckle-type couplers comprising unmachined castings are the A.A.R. (American Association of Railroads) approved E and F types used extensively in interchange service in the railroads of the United States. Generally speaking, these couplers are designed to maintain full operability and dependability regardless of the great variation in the wear of coupled couplers and the many other conditions attendant to use in interchange service. The design of these couplers is closely controlled to exacting physical and dimensional standards by the railroad industry and the coupler manufacturers.

Through long experience, the industries which manufacture and use the E and F types of couplers have evolved a set of tolerances within which a large number of standardized dimensions and contours of the couplers must conform. However, it has been obvious for some time that under very severe conditions of use a transverse deformation occasionally occurs in the head of a knuckle-type coupler which is characterized by an increase in the distance between the spaced lateral walls of the knuckle receiving-pocket. Such deformation adds to the longitudinal and lateral slack in the two coupled couplers and results in an increased wear rate. As a serious safety hazard, such deformation may be accompanied by fracturing of the coupler head.

It has been discovered that present contours of the knuckle-type couplers, while keeping within the requirements of the American Association of Railroads, fail to reliably provide for the proper absorption of buffing forces by the coupler head. Upon some of the couplers, the buffing forces appear to be absorbed at spaced points on opposite sides of the longitudinal axis of the coupler head and produce an undesirable wedging action between the knuckle of one coupler and the head of an opposing coupler. This is contrary to normal operation of such couplers, since a buffing force is intended to be transmitted from the front face of the knuckle of one coupler to the forwardly-facing rearward surface in the knuckle-receiving pocket of the other coupler in the longitudinal direction of the couplers. Disposition of these opposing surfaces at substantially right angles with the longitudinal axis of the couplers is consistent with the basic design of the couplers whereby strength is provided in essentially their longitudinal direction.

The present design of knuckle-type couplers in interchange service does not assure infallible occurrence of satisfactory face-to-face abutment of opposed couplers in buffing operations.

2

Accordingly, it is a primary object of this invention to provide standard knuckle couplers of modified design which are potentially capable of being coupled with the other couplers in interchange service without the possibility of producing or being subjected to substantial wedging forces in buff operation.

An object ancillary to the foregoing object is the provision of a coupler contour whereby buffing forces are transmitted through a coupling in essentially the longitudinal direction of the coupling but permitting vertical and horizontal angling within standards set by the American Association of Railroads.

Another object is to provide a coupler contour which will require no change in present standard knuckle construction as prescribed by the A.A.R. and will assure complete knuckle closure during coupling operations.

An additional object of this invention is to provide a coupler contour which will increase the efficiency of the coupler during operation and prolong its service life.

Still another object is to provide improved E and F types of couplers which will warrant approval of the Association of American Railroads for standard interchange service in substitution of the present E and F types in current railroad use.

The invention, in its broader aspects, consists of a knuckle-type car coupler comprising a head having a knuckle-mounting portion, a guard arm, and a buff section, the latter having a vertical forwardly-facing surface and extending transversely of the longitudinal axis of the coupler to connect rearward ends of the knuckle mounting portion and the guard arm whereby a pocket is formed for receiving the knuckle of an opposing coupler. The coupler also comprises a knuckle which is pivotally supported by the knuckle-supporting portion to cause the nose

of the knuckle to laterally overlap a portion of the pocket in coupled or locked position of the knuckle. In this position, the knuckle provides a forwardly-facing face which is substantially complementary to the face of the buff section of the head. The dimensions of the knuckle are variable within predetermined dimensional tolerance ranges. The knuckle-supporting portions and the guard arm are spaced transversely of the longitudinal axis of the coupler adjacent to where they join with the buff section surface to provide a transverse dimension of the pocket within a predetermined tolerance range. The spacing of the guard arm and the knuckle-supporting portion enable complete rearward displacement of the knuckle of another similar opposing coupler having maximum dimensions within the pocket named above when the transverse dimension thereof is a minimum in the tolerance range named above. In completing rearward displacement, the knuckle of the opposed coupler effects substantially full engagement of its face with the face surface of the buff section.

In the accompanying drawing with respect to which the invention is described:

Fig. 1 is a fragmentary top plan view showing the relationship between coupled couplers embodying the novel contour of this invention in buff position.

Fig. 2 is a fragmentary top plan view showing the new contour in an A.A.R. (Association of American Railroads) approved standard type F coupler with the old contour shown partially in dot-dash line.

Fig. 3 is a view similar to Fig. 2, showing the new contour in an A.A.R. approved standard type E coupler, the old contour again appearing partially in dot-dash line.

Fig. 4 is a fragmentary top plan view showing the relationship between coupled prior art couplers in buff position.

Fig. 5 is a fragmentary top plan view illustrating an undesirable relative disposition of engaged nose portions of a pair of coupled couplers.

Referring now to the drawing, there is illustrated in Fig. 1 two standard type F couplers A and B, each having a head 9 comprising the usual guard arm 10 with an integral forwardly extending projection 11 for complementally engaging the surfaces defining a pocket 12 of the opposite side 13 of an opposing coupler when in coupled position. Disposed intermediately of the arm 10 and the side 13 is a generally U-shaped pocket 14 adapted to receive the pivotal knuckle 15 of an opposing coupler. The pocket 14 is partially bounded by a transverse buff section 16 of the head which is substantially at right angles to the longitudinal draft axis X—X of the coupler. The buff section 16 provides a vertical forwardly-facing buffing surface 17, slightly laterally extended as at 16a and merging in a concave corner surface wherefrom the pocket wall extends forwardly and transversely outwardly as the inner guard arm surface 28. The knuckle 15 has a nose 7 and a front-facing transverse portion 20 which defines the front buffing face 18.

As illustrated in Fig. 1, the knuckle portion 20 on the opposed coupler abuts the transverse head section 16 with the resulting contact between the surface 17 and the face 18 of opposed couplers. In order to provide reasonable bearing stresses in buff operation, the surface 17 and the face 18 are substantially complementary. Hence, the buffing forces transmitted through the couplers, are applied to the head 9 of each coupler substantially in the direction indicated by the arrows in Fig. 1, parallel to the draft axis X—X of the couplers.

In order to obtain and maintain the above described relationship between the knuckle 15 and the pocket 14 in buff position, the diagonally extending inner side 28 of the guard arm 10 has been relieved, i.e., offset laterally, as compared with the standard E coupler design approved by the Association of American Railroads, and merges with the surface increment 16a to provide adjacent their juncture a clearance 8 in a manner which will hereinafter be described. In buff operation, a clearance 21 exists between the knuckles 15 which eliminates the tendency of the knuckles to engage and bend or bind relative to each other. In the buff operation of a pair of coupled couplers constructed in accordance with this invention, the couplers will align with (a) their longitudinal axes Y—Y coinciding with draft axis X—X of the coupling as a whole, (b) the front surface of the buff section of one coupler in substantially complementary relation with the knuckle face of the other coupler, (c) the nose of one coupler in approximate contact with the knuckle-supporting portion of the other coupler, (d) and a clearance between the inner guard arm surface of one coupler and the heel of the knuckle of the other coupler.

By way of comparison, the relationship in buff position between the parts of coupled A.A.R. standard type F couplers employing the prior art contour is illustrated in Fig. 4. Fig. 4 is illustrative of the misfit which occurs in the coupling of a pair of couplers having knuckles of the maximum size and pockets of the minimum size permitted within the dimensional tolerance ranges set by the Association of American Railroads.

As shown in Fig. 4, an undesirable clearance 22 exists between the front buffing surface 17 of the head 9 and the front buffing face 18 of the knuckle 15. Hence, no abutting contact occurs between the transverse portion 20 of the knuckle and the transverse portion 16 at the rear pocket 14, such as would operate to enable buffing forces to be absorbed by the head 9 and transmitted primarily in a direction parallel to the longitudinal axis X—X.

Instead, in the arrangement which occasionally occurs in the prior art system, as shown in Fig. 4, contact occurs between the heel 19 of knuckle 15 and the diagonal inner side 30 of the guard arm 10 at point H, and be-

tween the nose 7 and the side wall of the socket 14 at point J.

Thus, buffing forces are, in the prior art coupler of Fig. 4, absorbed by the head 9 at spaced points on opposite sides of the longitudinal axis X—X. Furthermore, it is evident that the buffing forces, indicated in an approximate manner by arrows B₁, B₂, B₃, and B₄ in Fig. 4, absorbed by the head 9 of either coupler, are multi-directional rather than being parallel to the coupler draft axis X—X and give rise to action tending to split the coupler heads. It will also be observed that little or no clearance exists between the knuckles 15, indicating the undesirable binding of the knuckles in buff along the draft surfaces thereof. It will be understood that the undesired clearance 22 is subject to variations from its form as shown on account of the standard (A.A.R.) allowable tolerances permitted in the casting of the coupler head and the knuckle.

In Fig. 2, the novel contour is illustrated in detail in connection with a standard type F coupler. Transverse line A—A is known as the pulling line and is located $3\frac{1}{16}$ inches forwardly of the pocket surface 17. According to the contour, as shown in solid lines, the surface of a transverse portion 16 merges with a curved surface 23, the latter in turn merging with the surface of an axially-aligned knuckle supporting lug or wall portion 24. The contour of portion 24, as viewed in plan terminates in that of the concavely curved throat 25 of the knuckle. The transverse pocket surface 17 and the incremental surface portion 16a added by this invention and provided by transverse head portion 16 merge with the concave curved surface 27 which in turn merges with the lateral diagonally extending pocket surface 28 of the guard arm 10. The surface 28 terminates at a point N on the guard arm 10. Due to normal variations in casting, a lateral surface on the knuckle rearwardly of the curve 25 may protrude slightly laterally beyond the surface 24 from between the upper and lower pivot or knuckle supporting lugs and be engaged by the nose of an opposing coupler.

The prior art contour, shown partially in dot-dash line, extends along the following surfaces, namely: curve 26, curved portion 25, axially aligned wall portion 24, curve 23, lateral surface 17, curve 29 (in dot-dash), and diagonally extending inner side 30 (in dot-dash) of the guard arm 10. As shown, the prior art contour terminates at the same point N on the guard arm 10 as does the novel contour. Hence, it may be noted that the novel contour and the prior art contour differ primarily in the disposition of the lateral surface of the pocket formed by the guard arm. As indicated in Fig. 2, curves 27 (novel contour) and 29 (prior art contour) of the F type coupler are struck with the same radius but the curve 27 is struck from a point which is located laterally a greater distance from the longitudinal center line of the coupler head than is the point from which the curve 29 is struck.

An increase in the lateral distance from the longitudinal center line of $\frac{1}{8}$ inch to strike the curve 27 has been found sufficient to accomplish the objects of this invention. Accordingly, laterally shifting the location of the strike point away from its draft or longitudinal axis Y—Y (common with axis X—X in Fig. 1), results in the transverse coupler head portion 16 being laterally extended an equal amount, as at 16a, and the inner side 30 (old contour) being relieved to form the new lateral pocket surface 28. Thus, the clearance 8 is provided in sufficient width to permit abutting relation between the front buffing surface on the head of one coupler and the front buffing face on the knuckle of another coupler to occur as previously described in all possible coupler dimensions within the standard tolerance ranges now in use.

However, the extent to which the lateral pocket sur-

face 28 in a type F coupler can be relocated in a direction away from the axis Y—Y must be no greater than that which will assure positive lock operation when opposed couplers are brought into position for coupling. Excessive relief of the inner guard arm surface 28 shown in Fig. 2 may provide too much freedom of the knuckle of one coupler in the pocket of the other coupler in a direction lateral to the longitudinal axis. As a consequence, the knuckle noses may interfere to such an extent as to prevent the split-second cooperation of coupler parts needed for successful coupler action.

Referring again to Fig. 1 and observing internally of the head 9, one side 71 of the tail 70 of the knuckle 15 abuts the inner side wall surface 73 of the head in buff position wherein the other side 74 of the knuckle tail has a clearance 75 of about $\frac{1}{4}$ inch with the head of the lock 76 in its lower locking position. This is the position of the knuckle most favorable to the descent of the lock to its locking position. In order for the lock to descend to its lower position with certainty, the clearance of the knuckle tail with that space occupied by the lock head must not be substantially diminished during the coupling operation.

Hence, it is necessary in a coupling operation that the longitudinal axes of both couplers come into substantially common alignment at the instant of coupler impact with the convex nose portion 26 mating substantially with the concave nose portion 25 of the opposed coupler. The knuckle of the unlocked coupler is thereby permitted to reach its full buff position wherein its tail engages the side wall of the head. However, if the pockets of the coupler are enlarged to the extent that the couplers seek to intercouple with their longitudinal axes separated, e.g., $\frac{1}{2}$ inch, the knuckles may engage along the rear convex nose surfaces 26 thereof, as shown in Fig. 5, (rather than by the convex surfaces 26 engaging the concave surface 25) to such an extent that the knuckle of the unlocked coupler cannot reach substantially its full buff position. The knuckle tail of the unlocked coupler is thereby unable to get into clearance with the path to be followed by the head of the lock as it attempts to descend into locking position.

To understand such a coupler failure, it is necessary to take into account the recoil and vibration of coupler parts that take place at the instant of coupler engagement in a coupling operation. Hence, the clearance 8 provided as shown in Fig. 1, between the guard arm of one coupler and the heel surface of the knuckle of the other coupler, must not be so great as to allow such lateral misalignment of the couplers as to bring about the condition shown in Fig. 5. In a coupling operation, the lock 76 of the unlocked coupler is raised and must have clearance with the knuckle tail 70 while descending to locking position. With the nose 7 in lateral interference as a result of excess axial misalignment of respective couplers, the clearance 75 may be reduced to less than the width needed for descent of the lock. In the standard F coupler, the clearance 8 should not exceed about $\frac{1}{8}$ inch in order to assure sufficient width of the clearance 75.

To assure that such sidewise relative displacement of type F couplers does not occur to hinder operation of the lock in the unlocked coupler, it is recommended that the point for striking the $1\frac{3}{4}$ -inch radius of the surface 27 be located at no greater than $3\frac{3}{4}$ inches from the longitudinal axis Y—Y. As shown, the striking point of the surface 27 is necessarily $1\frac{3}{4}$ inches forward of the point of tangency of the surface 27 with the pocket or buffing surface 17. This dimension is greater by about $\frac{5}{16}$ inch than in the prior art type F coupler. To assure that the coupler pocket will accommodate the maximum size knuckle permitted by the A.A.R. standards, this dimension should not be less than $3\frac{7}{16}$ inches (see Fig. 2). That is to say, this dimension is the minimum value in any tolerance range adapted.

A type E coupler is not correspondingly hindered in its locking operation because of the greater longitudinal clearances normally provided for the knuckle in the pocket of the opposing coupler. Assuming there was sufficient lateral clearance in the pocket of a locked E coupler, the longitudinal spacing between the pulling face of the knuckle and the buffing face at the rear of the pocket is sufficient to permit lateral passage of its knuckle past the knuckle of another coupler coupled without binding therewith. Hence, there is not such interference of the knuckle noses that would substantially reduce the internal clearance needed in the unlocked coupler for lock operation.

In the present invention, no change is contemplated in the prior art construction of the knuckles of standard type E or F couplers. On the knuckle 15, the curve 31 on the heel 19 is still struck with the same radius and from the same striking point laterally of the longitudinal center line heretofore used in the standard type F coupler, as shown in Fig. 2.

Fig. 3 illustrates a standard type E coupler (as approved by the Association of American Railroads) having a head 40 incorporating, as shown in solid lines, the novel contour of this invention. Transverse line B—B is known as the pulling line and is located $3\frac{25}{32}$ inches forward of the pocket surface 60. A standard construction B'—B' is $\frac{3}{32}$ inch forward of the pulling line. The contour comprises point M, a diagonally extending inner side surface 41, a curved surface 42, a buffing surface 60 on the transverse portion 43, a small extension 43a of the surface 60, a curved surface 44, an axially aligned surface on the wall portion 45, and curved surfaces 46 and 47 connected in series to provide a continuous surface. The prior art contour, shown partially in dot-dash lines, differs from the novel contour only in the diagonally extending surface 50 and the curved surface 51, as is seen in Figure 3. As with the type F coupler, the curves 42 and 51 are struck with the same radius but the curve 42 has its striking point located a greater lateral distance from the longitudinal center line than does the curve 51. In this case, increasing the lateral distance from the longitudinal center line from $3\frac{11}{32}$ inches (in the prior art structure) to $3\frac{15}{32}$ inches, i.e., by $\frac{1}{8}$ inch, in locating the strike point for the curve 42 was found sufficient to obtain desirable abutting contact between the transverse buffing portion 43 of the coupler head and the transverse portion 65 of the knuckle 61 on an opposed coupler.

However, in order to avoid unintentional slip-out or uncoupling of coupled E couplers, and allowing for wear and service deformation, such as "knuckle stretch," shifting of the striking point for the curve 42 should not exceed $3\frac{3}{4}$ inches from the longitudinal axis of the E coupler. This latter dimension exceeds the standard prior art measurement for locating the striking point by $1\frac{3}{32}$ inch, and the measurement for the new contour herein described by $\frac{3}{32}$ inch. The minimum allowable measurement for the E coupler consistent with the purposes of this invention is that shown by Fig. 3, i.e., $3\frac{15}{32}$ inches.

As illustrated in Figs. 2 and 3, it will be seen that there is no change in the opening existing between point N or M and the respective noses 7 or 62 of either the F or E type couplers since points N and M are also terminal ends of the pocket contours of the prior art E and F types, respectively. This feature serves to keep the pocket contour of this invention within the standards set by the Association of American Railroads regulating permissible horizontal and vertical angling between couplers. Also, in relieving the inner sides 30 and 50 to form the new inner sides 28 and 41, respectively, the latter are more steeply inclined rearwardly.

In either type of coupler illustrated, but taking the type F coupler as exemplary, considerable interference may occur between the knuckle of the unlocked or entering coupler and the knuckle nose and guard arm of the unlocked or receiving coupler, if the couplers approach each

other with a slight-to-moderate lateral misalignment. Such interference occurs particularly at an intermediate stage during coupling in which the knuckle of the unlocked coupler has but partially passed into the pocket of the locked coupler. The engagement at this instant is such that the heel of the unlocked knuckle slidably engages the inner guard arm surface under conditions of high pressure and abrasion. The unlocked knuckle is subjected also to a torque force which causes the pulling or rear side of its nose to slidably engage the pulling or rear side of the knuckle nose of the locked coupler.

The more longitudinally inclined inner guard arm surface provided by the present invention substantially reduces the pressure with which the unlocked knuckle initially engages the guard arm and knuckle of the opposing coupler of the prior art under the offset conditions described immediately above.

Hence, the coupling action of the couplers, improved as herein directed, is smoother and accompanied by greater certainty of coupling and less wear of the pocket and knuckle surfaces than in the standard prior art couplers. In further comparison, the serious attrition of coupler parts resulting from wedging which inevitably occurred in some of the previous couplers constructed within the standard A.A.R. prescribed dimensional tolerances, has been avoided by assuring that the knuckle face in one coupler will squarely engage the head buffing surface of an opposing coupler.

The terms and expressions which have been employed are used as terms of description and not of limitation and there is no intention of excluding such equivalents of the invention described or of the portions thereof as fall within the purview of the claims.

What is claimed is:

1. In a knuckle type car coupler comprising a head having a knuckle-mounting portion, a guard arm, and a buff section having a flat vertical forwardly-facing surface extending in a direction transversely of the longitudinal axis of the coupler to connect the rearward ends of said knuckle-mounting portion and the guard arm and forming thereby a pocket for receiving the knuckle of a similar coupler; a knuckle pivotally supported by said head comprising a tail extending rearwardly of the pivotal axis of the knuckle and a nose disposed forwardly of said axis; a lock movable along a path between an upward coupler-

45

unlocking position and a lower locking position beside the tail of the knuckle; said tail, in the buff position of the coupler, resting with one side thereof against an inner side wall surface of the head with a clearance between the other side of the tail and the path of the lock; the dimensions of said nose and said pocket being so related that, in the buff position of said coupler and a similar coupler intercoupled therewith wherein a knuckle of the similar coupler and identical with said knuckle has its face in substantially plane engagement with said buff section surface and its nose in engagement with said knuckle mounting portion, the horizontal dimension of the pocket in a vertical plane normal to the longitudinal axis in parallel adjacent relation with said section surface is greater, at a minimum value, than the horizontal dimension of the nose of said identical knuckle to form a clearance between the rear portion of the guard arm and the heel of said identical knuckle and, at a maximum value, limiting such clearance to a width preventing rotation of the tail away from said wall surface through said clearance between the tail and the path of the lock into said path.

2. A coupler according to claim 1 and typified by the Association of American Railroads' standard type F coupler wherein: the juncture of the guard arm and the buff section provides a concave arcuate surface generated by a $1\frac{1}{4}$ -inch radius having its striking point $1\frac{3}{4}$ inches forwardly of said surface of the buff section and in the range of from $3\frac{1}{16}$ to $3\frac{3}{4}$ inches as measured in a horizontal plane including the longitudinal axis of the coupler from said axis.

3. A coupler according to claim 1 and typified by the Association of American Railroads' standard type E coupler wherein: the juncture of the guard arm and the buff section provides a concave arcuate surface generated by a $1\frac{1}{4}$ -inch radius having its striking point $1\frac{3}{4}$ inches forwardly of the point of tangency of said arcuate surface and in the range of $3\frac{1}{16}$ to $3\frac{3}{4}$ inches as measured in a horizontal plane including the longitudinal axis of the coupler from said axis.
